JOIST

Samuel F. McIntosh, Scarsdale, N. Y.

Application September 6, 1945, Serial No. 614,699

3 Claims. (Cl. 189—40)

1

This invention has general reference to steel joists and the same has particular reference to an improved joist of the open web metallic bar type which is constructed and arranged for supporting concrete floors and the like and which provides nailing strips for securing wooden flooring thereto in overlying relation with the concrete floors.

The invention primarily comprehends a metallic joist of the aforesaid character in which a metallic bar bent at longitudinally spaced points into undulating formation constitutes the web thereof and which is provided with longitudinally extending top and bottom chords secured to the curved top and bottom portions of the undulations, the top chord being so constructed as to provide laterally projecting flanges adapted to extend under and support concrete floors and which defines an upwardly opening channel for receiving a nailing strip to which wooden flooring is secured in overlying relation with the concrete floors.

The invention further includes angle clips extending under and secured to the opposite ends of the upper chord of the joist and having flanged upper ends adapted to engage over horizontal girders for supporting the same in spanning relation therebetween without the necessity of employing rivets, bolts or other fastening means.

The invention also has in view the provision of a bottom chord formed with a downwardly opening channel for receiving a nailing strip to which plaster-board, fibre-board and the like is adapted to be secured to form a ceiling structure.

With the aforesaid and other objects in view reference is now made to the following specifications and accompanying drawings in which the preferred embodiments of the invention are illustrated.

In the drawings:

Fig. 1 is a view in elevation of a joist constructed in accordance with the invention.

Fig. 2 is an enlarged vertical sectional view taken approximately on line 2—2 of Fig. 1 and illustrating the joist supporting concrete and wooden flooring.

Fig. 3 is a fragmentary top plan view of one end thereof.

Fig. 4 is a fragmentary vertical sectional view of a modified form of lower chord.

Referring to the drawings by characters of reference the joist designated generally by the reference character A is illustrated in the drawings with its opposite ends supported by two horizontally disposed channel girders B.

The joist A includes a web 10 consisting of a bar fashioned of steel or other suitable metal which bar is bent at longitudinally spaced points into undulating formation so as to provide upper and lower longitudinally spaced reversely curved

2

portions 11 and 12 and diagonally extending straight portions 13 joining the upper and lower curved portions. Secured to the upper and lower curved portions 11 and 12 of the web are longitudinally extending top and bottom chords 14 and 15 respectively.

The top chord 14 consists of longitudinally extending mating members 16 each fashioned so as to provide a longitudinally extending side wall 10 including a vertically disposed upper wall portion 17 and a longitudinally disposed inwardly projecting lower wall portion 18 of V formation in cross-section and top and bottom horizontally disposed flanges 19 and 20 projecting inwardly and outwardly respectively at the upper and lower edges of the said side wall. The said mating members 16 are arranged in confronting spaced relation on opposite sides of the web 10 so as to provide a longitudinally extending upwardly opening channel 21 therebetween which is defined by the side wall portions 17 and the inwardly directed V shaped wall portions 18 of said mating members, the latter portions forming the bottom wall of the channel. The said V shaped wall portions 18 also define a longitudinally extending recess 22 in the underside of the chord 14 in which recess the upper curved portions 11 of the web 10 are disposed in engagement with the medial portions of the inwardly directed side wall portions 18 and to which the said curved portions of the web 10 are secured by welding material 23.

The longitudinally extending channel 21 of the chord 14 has arranged therein a nailing strip 24 of wood or other suitable material which is secured therein by the inwardly directed flanges 19 which overlie the opposite longitudinal edge portions of the strip and in addition thereto nails or other securing means 25 extending through the side wall portions 17 of the mating members 16 have their inner ends anchored in said nailing strip 24.

The bottom chord 15 consists of a pair of longitudinally extending angle bars 26 which are disposed on opposite sides of the web 10 with the vertical flanges 27 thereof abutting against the opposite sides of the lower curved portions 12 of said web and to which said angle bars are secured by welding material 28.

Constructed in this manner the horizontally disposed longitudinally extending bottom flanges 20 of the top chord 14 project under and provide a support for concrete flooring sections C on each side of the joist while the longitudinally extending nailing strip 24 is adapted to provide means for securing wooden flooring D thereto in overlying relation with the concrete flooring sections C and the horizontally disposed longitudinally extending flanges 26 of the bottom

chord 15 are adapted to provide supports for a ceiling structure.

The joist A is suspended between the channel girders B by means of angle clips 30 which hook over the upper flanges of the girders respectively whereby the joist is retained in position on the girders by the weight of the joist and the flooring carried thereby without the necessity of utilizing rivets connecting the clips with the girders. The clips 30 each consist of a vertically disposed web 31 having an outwardly extending horizontal flange 32 at the upper end thereof and an inwardly extending horizontal flange 33 at the bottom thereof, the upper flange 32 being formed with a down turned free end or lip 34. The clips 30 are secured to the opposite ends of the upper chord 14, the ends of the mating members 16 thereof being disposed in abutting engagement with the webs 31 and with the flanges 20 of said mating members supported upon the lower flanges 33 of the clips. The clips are secured to the chord 14 by spot welding the same as indicated by the welding material 35, the lower chord 15 being spot welded to the girders B as indicated by the welding material 36. The clips are preferably secured to the upper chord 14 during the assembly of the joist whereby the joist may be lifted bodily and disposed in position on the girders B with the down turned ends or lips 34 engaging over the outer ends of the upper flanges of the girders B.

Instead of the bottom chord 15, the joist A may be provided with a bottom chord 37 as illustrated in Fig. 4 of the drawings. The chord 37 includes longitudinally extending mating members 38 each of which consists of a side wall including a longitudinally extending lower vertical wall portion 39 and a longitudinally extending inwardly directed upper wall portion 40, the lower wall portion having an inwardly directed flange 41 at the lower horizontal edge thereof. The mating members 38 are arranged in confronting spaced relation on opposite sides of the web 10 so as to provide a longitudinally extending downwardly opening channel 42 defined by the vertical side wall portions 39 and the inturned upper wall portions 40, the latter forming the bottom wall of the channel. The inturned wall portions 40 are recurved outwardly at their inner extremities which recurved portions are disposed in engagement with the opposite sides of the lower curved portions 12 of the web 10 to which said curved portions of the chord 38 are secured by welding material 43.

A nailing strip 44 of wood or other suitable material is arranged within the channel 42 providing means for securing a ceiling structure to the bottom of the joist. The nailing strip 44 is retained within the channel 42 by means of the inwardly directed flanges 41 and by nails 45 or other fastening elements extending through the side wall portions 39 and having their inner ends anchored in the said nailing strip.

What is claimed is:

1. In a structural joist, a web consisting of a bar bent at longitudinally spaced points into undulating formation to provide upper and lower longitudinally spaced reversely curved upper and lower portions joined by diagonally extending straight portions, upper and lower chords extending longitudinally of said web and secured to said curved portions respectively, said upper

chord consisting of oppositely disposed mating members each including a longitudinally extending upper wall portion, a longitudinally extending inturned lower wall portion and longitudinally extending top and bottom horizontally disposed flanges projecting inwardly and outwardly respectively at the upper and lower edges of said wall portions, said mating members being disposed on opposite sides of the web with the inturned lower wall portions thereof secured to opposite sides of the upper curved portions of the web to thereby provide a longitudinally extending upwardly opening channel between said mating members and a longitudinally extending nailing strip arranged in said channel with the inwardly directed flanges thereof overlying opposite longitudinal edges of said nailing strip to thereby provide means for securing a wooden flooring upon a concrete floor supported by said outwardly directed lower horizontal flanges.

2. In a structural joist, a longitudinally extending web, upper and lower chords extending longitudinally of said web and secured to the top and bottom edge portions thereof, said upper chord consisting of oppositely disposed mating members each including a longitudinally extending upper wall portion, a longitudinally extending inturned lower wall portion and longitudinally extending top and bottom horizontally disposed flanges projecting inwardly and outwardly respectively at the upper and lower edges of said wall portions, said mating members being disposed in spaced relation on opposite sides of the web to thereby provide a longitudinally extending upwardly opening channel therebetween for receiving therein means for nailing a wooden flooring upon a concrete floor supported by said outwardly directed lower horizontal flanges with the horizontally disposed top flanges extending inwardly in overlying relation with the longitudinal edges of said means within the channel.

3. In a structural joist, a longitudinally extending web, upper and lower chords extending longitudinally of said web secured to the upper and lower edge portions thereof, said upper chord including laterally spaced longitudinally extending members located on opposite sides of said web each including a longitudinally extending horizontally disposed flange projecting outwardly at the lower edge thereof and providing an upwardly opening channel between said spaced members above said web for receiving therein means for securing a wooden flooring upon a concrete floor supported by said longitudinally extending horizontally disposed flanges.
